RADIATOR HEATER

Filed August 26 1925 2 Sheets-Sheet 2

UNITED STATES PATENT OFFICE.

ERNEST EMIL GRABNER, OF BALTIMORE, MARYLAND.

RADIATOR HEATER.

Application filed August 26, 1925. Serial No. 52,709.

This invention relates to a radiator heater, and particularly to a construction adapted for application to an automobile radiator for the purpose of heating the water therein

5 independent of the engine whenever found necessary or desirable.

In previous constructions of this character the heaters used have been so slow in action that considerable time was required to set 10 cure sufficient increase in temperature in the water for the proper starting and operation of the engine, particularly under cold weather conditions. I have therefore found it desirable to provide an improved type of 15 water heater by which the temperature of the liquid may be quickly raised and as a considerable body of liquid is involved this reduces the time necessary to securing a proper temperature for the starting of the 20 engine.

The heater is also so constructed and connected as to be always ready for operation by its circulating connection with the radiator and does not affect the ordinary engine 25 circulation when the automobile is under operation.

In the previous types of radiator heaters it has been more or less inconvenient to 30 ignite the same, requiring in some cases a pilot burner, and the control of the burner has not been accessible to the operator of the machine at the dashboard connection. I have therefore provided means by which 35 an electric ignitor cooperates with the wick of the heater so as to avoid the necessity of maintaining a constant or pilot light and also providing means by which a spark may be directly applied to the wick for its immediate ignition when desired. Means are 40 also provided for the regulation of the wick to control the position thereof and the consequent heating capacity of the burner relative to the boiler disposed in the flue communicating therewith.

45 The invention has for an object to provide an improved type of heater having a water space with a substantially corrugated radiating wall, said space being in circulating connection with a radiator and the flue within 50 said corrugated wall being in communication with a heating burner.

Another object of the invention is to provide a tubular water heater in circulation with the radiator and having a heating

chamber disposed above the discharge for 55 the products of combustion and connected with the tubular heater by a series of conducting tubes.

A further object of the invention is to provide an electric connection for igniting 60 a heater and comprising a sparking coil having a secondary circuit connected with a contact disposed at the point of ignition of the heater and insulated from the body thereof, together with a return circuit from the fuel receptacle of the heater which is otherwise insulated from the engine structure and casing.

Other and further objects and advantages 70 of the invention will be hereinafter set forth and the novel features thereof defined by the appended claims.

In the drawings:

Figure 1 is a longitudinal section showing 75 the invention applied to an automobile radiator;

Figure 2 is an enlarged section on the line 2-2 of Figure 1;

Figure 3 is a rear view of a radiator with 80 the heater applied;

Figure 4 is a vertical section through the 85 heater and burner;

Figure 5 is a section on the line 5-5 of 90 Figure 4;

Figure 6 is a similar view on the line 6-6 95 of Figure 4;

Figure 7 is a like view on the line 7-7 100 of Figure 4;

Figure 8 is a section on the line 8-8 of 105 Figure 4; and

Figure 9 is a detail section of the yielding support for the burner.

Like reference numerals designate corresponding parts throughout the several figures of the drawings.

This construction of radiator heater is applicable to various uses such as the heating of liquid for a stationary radiator, but is particularly adapted and shown in connection with an automobile radiator in 100 which it is desirable to quickly raise the temperature of the water in order to secure a proper starting of the machine and its even operation under varying temperatures of the atmosphere.

In the form of the invention shown, the numeral 10 designates a heater which comprises specifically an outer tubular shell 11

and an inner substantially corrugated shell 12 forming an intermediate water space 13 which is in communication with a radiator 15 at its lower portion by means of any desired form of connection as shown at 16. The discharge from the heater is likewise connected with the upper portion of the radiator by means of a connection as at 17. The construction of the substantially corrugated inner wall of the water chamber provides the maximum radiating surface in communication with the products of combustion from the heater 18 which pass upward through the flue 19 formed by the corrugated wall. The specific form of corrugation shown involves the ribs 20 of outwardly increasing diameter and connected at their base by which the most efficient heating is secured.

20 The water space 13 is enlarged at the upper discharge end of the heater to form a chamber 21 from which a series of connecting pipes or tubes 22 extend upon arcuate lines to a superheater 23 which is supported there- 25 by directly above the discharge from the vertical flue 19. The under surface of this heater is curved and causes the products of combustion to be deflected outwardly in opposite directions while the liquid passing 30 through the tubes 22 and the chamber 23 becomes superheated and is discharged from the latter at 24 into the return connection 17 to the radiator. This radiator is connected with the engine 25 in the usual 35 manner as indicated by dotted lines in Figure 1, and by heating the water therein to establish a circulation the engine is preliminarily heated before being started.

For the purpose of applying heat to the heater various forms of burners may be used, a convenient type being that of an oil burner as shown at 18. The wick 26 of such a burner extends into the fuel receptacle 27 in the usual manner and surrounds the air intake 28 common to this type of burner. The heater 10 is supported above the burner by means of a casing 29 which if desired may be provided with glazed sight openings 30 and a closure or door 31 for access to the burner. The wick of the burner is adapted to be raised and lowered to control the degree of heat generated therefrom by means of a dashboard connection which comprises essentially a crank lever 32 mounted upon the receptacle and having its arm 33 connected with the wick raising rod 34. From this lever an operating rod 35 extends to the dash 36 of the machine where it is connected to a hand lever 37 adjustably operating upon an arcuate sector 38. By this means an accurate and delicate adjustment of the wick may be effected to secure the desired rapidity of heating at the burner.

65 Since such a burner is not continuously

used, I have provided electrical means for igniting the wick or other form of burner and controlled from the instrument board. This means comprises a sparking or transformer coil 40 having its primary circuit 10 connected to a battery 41 by a leader 42 and the opposite terminal of its primary being extended by a line 43 to a switch 44 upon the instrument board 45. The return circuit 46 from this switch extends to the opposite 15 side of the battery 41. The secondary circuit from the coil comprises the line 47 which is connected by means of a terminal 48 in circuit therewith and mounted in an insulated block or base 49 within the casing 20 50 of the burner. This terminal is adapted to discharge its spark into direct contact with the wick or burner as indicated in Figures 2 and 3. In order to prevent this high tensioned circuit from being transmitted to 85 the engine members where it might affect the spark distributing system, a return line 50 is provided from the fuel receptacle and has a contact 51 at the upper portion there- 90 of. This return line forms the opposite side 95 of the secondary circuit from the coil 40.

In connection with this circuit system the fuel receptacle 27 is supported upon insulating blocks 52 and such a support is of a yielding character so as to prevent splashing or loss of the fuel and also form a yielding support for the burner. Such support comprises the posts 53 extending from the blocks 52 and carrying screw rods 54 which pass through the upper end of an enclosing sleeve 55 within which a coil supporting spring 56 is disposed in contact with the upper face of the post 53. This sleeve is secured to the receptacle 27 at substantially the four corners thereof.

The general operation of the invention will be apparent from the foregoing description from which it will be seen that the heater provides a simple and convenient means for quickly raising the engine temperature when it is desired to start a cold engine, thus greatly economizing in the time required and in the strain upon the battery incident to repeated starting. A heater of this character is only practical and efficient 110 in accordance with the rapidity with which the temperature of the water can be raised, and therefore special designs have been embodied to superheat the water and establish a circulation thereof from the heater to the engine in the shortest possible time. It will be obvious that the connections for the regulation of the burner and for the ignition thereof from the dashboard form a very 115 convenient means for its control and avoid the necessity of opening the engine hood or coming into direct contact with the heater.

While the specific construction of the several parts has been shown and described, the invention is not confined thereto as 120

changes and alterations may be made therein without departing from the spirit of the invention as defined by the appended claims.

Having thus described my invention,
5 what I claim as new and desire to secure
by Letters Patent is:

1. In a radiator heater, a burner and fuel
receptacle, insulated supports for the recep-
tacle, a sparking igniter having a terminal
10 mounted in an insulating body surround-
ing the burner and terminating at the ig-
nition point of said burner, a burner casing
carried by said insulating body, and a ter-

15 minal upon said receptacle for establishing
circuit through the burner independent of
the support for the fuel receptacle.

2. In a radiator heater, a burner and fuel
receptacle, insulated blocks having posts with
interposed springs for supporting said recep-
tacle, a sparking ignitor having an insulat-
ed terminal adjacent said burner and a ter-
20 minal upon said receptacle, and means op-
erable from a remote point for controlling
said burner.

In testimony whereof I affix my signature.
ERNEST EMIL GRABNER.
